UNITED STATES PATENT OFFICE.

NICOLA DE MAIO, OF NEW HAVEN, CONNECTICUT.

PIPE ATTACHMENT.

1,098,942.

Specification of Letters Patent.

Patented June 2, 1914.

Application filed October 27, 1913. Serial No. 797,656.

To all whom it may concern:

Be it known that I, NICOLA DE MAIO, a citizen of the United States, residing at New Haven, in the county of New Haven and State of Connecticut, have invented certain new and useful Improvements in Pipe Attachments, of which the following is a specification, reference being had therein to the accompanying drawings.

10 My invention relates to a new and improved attachment for tobacco pipes, having for its object, among other things, to provide a simple device that may be inserted within the bowl of a pipe to hold the tobacco away from the bottom thereof; to provide an absorbent that will prevent the passage of nicotin through the stem of the pipe; that is adapted to be easily inserted or withdrawn; and provided with means 15 whereby it may be adjusted for pipes of various sizes; and so designed that the absorbent material will be removed from the pipe with the device itself.

To these, and other ends, my invention 20 consists in the pipe attachment, having certain details of construction and combinations of parts, as will be hereinafter described, and more particularly pointed out in the claims.

30 Referring to the drawings, in which like numerals of reference designate like parts in the several figures; Figure 1 is a fragmentary sectional elevation of a tobacco pipe having my attachment applied thereto; and Fig. 2 is an enlarged side elevation of the attachment complete.

In the embodiment of my invention there is provided a circular disk 1, having one or more openings 2 therethrough, and 40 threaded therethrough, adjacent to the outer edges thereof, is the spring finger 3. This finger is preferably constructed of flexible wire, terminating at each end in the eye 5—5, and, among its other functions, 45 holds the disk within the bowl by a frictional contact with the sides thereof, secures the mass of absorbent material 4 to the disk, and provides means for readily inserting and removing the attachment from the pipe itself. The absorbent material 4 is preferably a small sponge, and is held against the plate 2 by the loop formed in the member 3 beneath the disk, which loop is enlarged or reduced in size by a shifting of

the relative position of the spring finger 3 55 with the disk 1.

My attachment is applied to a pipe in substantially the manner shown in Fig. 1, with the absorbent material 4 lying against the bottom of the bowl and covered by the 60 disk 1, the ends of the spring fingers 3 having frictional engagement with the inside of the bowl. The opening 2 through the disk, and the open space between the periphery thereof and the inside of the bowl, 65 are utilized for the draft to pass therethrough. If the bowl of the pipe is of less height than that shown in the drawing, and it is not desired that the spring fingers 3 should project above the top thereof, the 70 position thereof in relation to the disk 1 is changed so that the eyes 5—5 at the ends thereof are brought nearer to the same horizontal plane, that is, the eye at one end is moved to a lower plane than that shown in 75 Fig. 1, and the eye in the other end to a higher plane. This adjustment is accomplished without affecting the hold of the loop upon the absorbent material underneath the disk. A pull exerted by the finger 80 upon one or both of the eyes 5 readily removes the attachment from the pipe.

Minor changes and alterations may be made in the details of my invention, and I do not therefore limit myself to the exact 85 construction herein shown and described, but claim all that falls fairly within the spirit and scope of my invention and the appended claims.

What I claim as new and desire to secure 90 by Letters Patent, is:

1. In an attachment of the character described, the combination with a perforated disk; of a flexible member connected therewith in such manner as to permit movement 95 thereof in relation to said disk; and an absorbent material secured to said disk by said flexible member.

2. In an attachment of the character described, the combination with a perforated 100 disk; of a flexible member connected therewith in such manner as to form a loop of variable size upon one side thereof; and an absorbent material secured to said disk by said loop.

3. In an attachment of the character described, the combination with a perforated disk; of a flexible member connected there-

with in such manner as to form a loop of variable size upon one side thereof with projecting ends upon the opposite side thereof; and an absorbent material secured 5 to said disk by said loop.

4. In an attachment of the character described, the combination with a perforated disk; of a flexible member connected therewith in such manner as to provide a loop 10 upon one side thereof and the relative lengths of the opposite ends thereof upon the opposite side of said disk may be varied; and an absorbent material secured to said disk by said loop.
- 15 5. In an attachment of the character de-

scribed, the combination with a perforated disk; of a flexible member connected therewith in such manner as to provide a loop of varying sizes upon one side thereof and the relative lengths of the opposite ends 20 thereof upon the opposite side of said disk may be varied; and an absorbent material secured to said disk by said loop.

In testimony whereof I affix my signature in presence of two witnesses.

NICOLA DE MAIO.
